CLAIM

The ornamental design for a combined handle base and clasp, as shown and described.

DESCRIPTION

FIG. 1 is a perspective view of a combined handle base and clasp showing my new design, the portion of a suitcase being shown in broken lines for illustrative purposes only;

FIG. 2 is an exploded enlarged top plan view thereof; FIG. 3 is an end elevational view taken from the bottom of FIG. 2, the side opposite being a mirror image; FIG. 4 is a bottom plan view of FIG. 2;

FIG. 5 is an elevational view taken in the direction of the arrows on line 5—5 of FIG. 2;

FIG. 6 is an elevational view taken in the direction of the arrows on line 6—6 of FIG. 2;

FIG. 7 is an elevational view taken in the direction of the arrows on line 7—7 of FIG. 2;

FIG. 8 is an elevational view taken in the direction of the arrows on line 8—8 of FIG. 2; and

FIG. 9 is an enlarged perspective view thereof.
